UNITED STATES PATENT OFFICE

BERNHART A. BENSON, OF CHICAGO, ILLINOIS, ASSIGNOR TO CHICAGO ELECTRIC MANUFACTURING COMPANY, OF CHICAGO, ILLINOIS, A CORPORATION OF ILLINOIS

OSCILLATING ELECTRIC FAN

Application filed December 28, 1931. Serial No. 583,435.

My invention relates to the general class of fan motors in which the motor and fan assembly is arranged so as to oscillate about an axis which is upright when the axis of the fan is horizontal, thereby distributing the blast of air from the fan through a considerable arc.

In some of its general aspects, my invention aims to provide a simple and inexpensive mechanism whereby the rotation of the fan shaft effects this oscillation, and aims to arrange this mechanism so that it can readily be employed in an electric fan which is also arranged so that the axis of the fan can be tilted upward or downward to vary the height at which the blast of the fan is directed.

In another object, my invention aims to provide simple means whereby the action of the oscillating mechanism can readily be annulled when desired, so as to convert the electric fan into a non-oscillating type when the blast of air is wanted continually in one direction. In this connection, my invention aims to provide such an electric fan with a cover housing the usually sharp-edged rear shaft portion and the worm-wheel meshing with the same, and aims to utilize this cover also as a support for the oscillation-controlling means.

Furthermore, my invention aims to provide an oscillation-effecting mechanism including a worm-wheel in which the teeth will be cut automatically during the initial operation of this mechanism, and aims to dispose other parts of this mechanism so that they will adjust themselves automatically to the gradual wear on the worm-wheel.

Still further and also more detailed objects will appear from the following specifications and from the accompanying drawings, in which drawings

Fig. 1 is an elevation of an interchangeably oscillating and non-oscillating electric fan motor of a table type embodying my invention, taken somewhat from the rear and with the lower portion of the usual pedestal broken away.

Fig. 2 is a similar elevation with the gear-concealing cover detached.

Fig. 3 is an elevation taken from the side of the electric fan which is at the left in Fig. 2.

Fig. 4 is a horizontal section taken along the line 4—4 of Fig. 3 and looking upward.

Fig. 5 is a fragmentary and enlarged side elevation taken along the line 5—5 of Fig. 3.

Fig. 6 is an upward section similar to Fig. 4, but taken after the worm-wheel has rotated sufficiently to swing the axis of the fan almost to one extreme position, including portions of the fan member.

Fig. 7 is a fragmentary and enlarged elevation taken from the line 7—7 of Fig. 3.

Fig. 8 is an enlarged and fragmentary section, looking upward from the line 8—8 of Fig. 3.

Fig. 9 is a top view of my electric fan, with the gear cover detached and a portion of the motor broken away, and with the pivoting stirrup omitted, showing the oscillation-effecting mechanism at one extreme of the same parts at the other extreme.

Fig. 10 is a vertical section taken through the detached gear cover along the line 10—10 of Fig. 1.

Fig. 11 is a fragmentary horizontal section through the gear cover and the adjacent part of the casing of the motor, along the line 11—11 of Fig. 1, with the oscillation-controlling lever in the position in which it annuls the oscillating of the fan.

Fig. 12 is a section similar to the lower portion of Fig. 11, with the oscillation-annulling lever in its inoperative position.

Figure 13 is an end elevation of the cover for the oscillating mechanism tilted forward showing the oscillation-annulling lever in operative position but spaced from the worm shaft 15.

In the drawings, Figs. 1 to 4 include the upper portion 1 of a customary fan-supporting pedestal having its upper end forked to receive a lug 2 between the arms of the fork. Extending through the two fork arms 3 is a horizontal thumb-screw 4 upon which the lug 2 is pivoted; this screw extending freely through one arm of the fork and being threaded into the other fork so as to clamp the fork arms against the lug. Swiveled to

the upper end of the lug 2 on a pivot element 6 (Figs. 3 to 5) is the horizontal back of a stirrup 7 which bears against the bottom of the casing 8 of an electric fan motor 9, and which stirrup supports the motor and its casing with freedom for oscillating about the axis of the pivot element 6.

Projecting toward one side from the lug 2 above the fork arms 3 of the pedestal, and desirably in the same direction in which the tip of the thumb-screw 4 extends, is a lug arm 10 to which one end of a link 11 is pivotally connected by a screw 12. The other end of the link 11, which desirably extends in a generally horizontal direction, is pivotally connected by a pin 13 to an arm 14 which is considerably shorter than the link 11. This arm 14 is fastened to the lower end of a worm-shaft 15 which has its upper end fastened to a worm-wheel 16, the worm-shaft being approximately upright and the worm-wheel having its faces substantially horizontal.

A bracket 17 is attached to the rear of the motor casing 8 by bolts 18, which may be part of the bolts connecting two interfitting casing portions to each other and to the stationary portion 9 of the motor. As here shown, this bracket 7 also has the rearward motor shaft bearing 19 attached to it, in alignment with a rear casing opening 8^A (Fig. 11) through which the shaft 20 of the motor projects, this projecting shaft portion being threaded for meshing with the worm teeth of the worm wheel 16 when the periphery of that wheel is pressed against the shaft.

To support and guide the worm-wheel and its own shaft for this purpose, I provide the bracket 17, at the same side of the motor toward which the lug arm 10 extends, with superposed rearwardly extending arms 21 and 22 through both of which the worm-shaft 15 extends, these arms having their faces parallel to the axis of the motor shaft 20. The lower of these arms (21) is above and desirably relatively near to the shorter link 14, and has a perforation 23 through which the worm shaft extends, this perforation being slightly larger in diameter than the worm shaft.

The companion perforation 24 in the upper bracket arm 22, through which the worm shaft also extends, is a slot having its longer axis A (Fig. 8) at right angles to the axis of the motor shaft 20; the width of this slot being desirably such as to guide the worm shaft slidably, while the length of the slot is considerably greater than the diameter of the worm shaft so as to permit a movement of the latter toward and away from the motor shaft.

Threaded upwardly through the upper bracket 22 is a screw 25 which extends through a loop in a wire spring 26 as shown

in Fig. 8. This spring has one end portion 26 A in engagement with the outward lateral edge of the bracket 17 and has its other end portion 26 B hooked over the worm shaft 15, as also shown in Fig. 3. The spring is wound around the shank of the screw 25 in such a direction that this spring continually tends to press the upper end of the worm shaft toward the right in Fig. 8 for causing the motor shaft 20 to be engaged by the worm-toothed periphery of the worm-wheel 16, this worm-wheel being spaced upwardly from the upper bracket arm 22 by a washer 28 as shown in Figs. 3 and 7 so that this washer supports the worm-wheel and its shaft.

Thus arranged, the link 11 and the arm 14 on the shaft of the worm-wheel form portions of a linkage operatively connecting the lug 2 (on which the motor is pivoted) with the motor and fan assembly, which assembly includes the motor shaft and the fan-blade member 29 fastened to the forward end of this motor shaft for oscillating this motor assembly about the axis of the pivoting stirrup 7 which rigidly supports that assembly.

That is to say, since the arm 14 on the shaft 15 of the worm-wheel extends radially of that shaft, each rotation of the worm-wheel will gradually swing the arm 14 from the position shown in dotted lines in Fig. 9 (in which this arm aligns with and extends from the worm-wheel shaft above the link 11 toward the screw 12 which pivots the inner end of that link to the stationary lug 2) to the other extreme position shown in full lines in Fig. 9 and somewhat approximated in Fig. 6. In this other extreme position, the arm 14 is disposed as an effective elongation of the link 11, so that in moving from one to the other extreme of its positions, the linkage considerably changes the distances between the screw 12 on the stationary lug and the shaft 15 of the worm-wheel.

Since the lug 2 is stationary, the just recited changes in the position of the two parts of the linkage results in swinging the motor and fan assembly about the pivoting axis of the stirrup 7, thereby swinging the axis of the air blast from the line L of Fig. 9 to the line R in the same figure, and thereafter back to the line L. This continuous oscillation is unaffected by any change in the lug axis 30 (Fig. 3) with respect to the upright axis of the pedestal, so that the fan can still be adjusted in the usual manner for raising or lowering the blast of air.

To avoid the high cost of cutting exact worm teeth on the worm-wheel 16 and of providing the rear portion of the fan shaft 20 with a specially shaped thread for mating with such worm teeth, I preferably cut an ordinary screw thread on this rearward shaft portion and depend on this thread for cut-

ting the worm teeth on the initially cylindrical periphery of a disk which is of softer material than the metal of the shaft. For this disk, I have found that a simple centrally perforated cylindrical disk punched from a sheet of vulcanized fibre will suffice, owing to the yielding pressure of the disk against the threaded fan shaft by the spring 26.

When the initially cylindrical periphery of such a disk is spring-pressed against the motor shaft (which here is also the fan shaft), this pressure immediately causes the thread on the shaft to revolve the disk when the shaft rotates, and even an ordinary die-cut thread will soon indent the periphery of the disk with the needed worm-teeth formations. Moreover, the yieldable mounting of the shaft of the worm-wheel allows that shaft to be pressed further toward the fan shaft when the fibre gradually wears, this being permitted by elongating the slot 24 in the upper bracket arm 22 so that the shaft 15 of the worm-wheel is freely spaced (during the initial installation of my electric fan) from the slot end nearest to the fan shaft even when the latter shaft is engaged by the worm-wheel as shown in Fig. 8. This use of a simple punching of hard fibre or the like for the needed worm-wheel also makes the cost of replacing that wheel quite nominal.

To allow my appliance to be used selectively as a non-oscillating fan, I provide an oscillation-controlling member movable into and out of a position in which it holds the worm-wheel freely spaced from the fan shaft, and I preferably dispose this member for engaging the shaft of the worm-wheel above and near the lower bracket arm 21, which is the bracket in which the worm shaft has the least play. I also preferably support this oscillation-controlling member on a cover which conceals both the worm-wheel and the threaded fan shaft portion, and which cover guards these relatively sharp-edged parts from contact with the hands of the user of my electric fan. Furthermore, I desirably employ this cover as a support for the switch which controls the circuit to the fan motor.

For these last named two purposes Fig. 1 and Figs. 10 to 13 inclusive show a forwardly open dome-like cover 31 bearing at its mouth end against the rear face of the motor casing 8, this cover being provided at its opposite sides with forwardly projecting spring fingers 32. These fingers are spaced so that they will respectively extend through two slots 33 (Fig. 2) in the rear wall of the motor casing 8 and hook against the inner face of that wall as shown in Fig. 11, thereby releasably securing the cover to the motor casing which in itself is fastened to the stator or stationary portion of the motor.

The cover desirably includes a top portion

31^A which slopes rearwardly downward and which has a slot 34 through which the actuating knob 35 of a switch 36 projects. This switch is fastened to the cover top portion by rivets 37 and is connected to the motor 9 by wires 38 which are left sufficiently slack to permit the cover to be swung away from the motor casing (for oiling the rear bearing 19) without detaching the wires. To permit such a movement of the cover, I provide a forwardly downwardly sloping cover bottom portion 31^B with an upright slot 39 which opens at the lower edge of that cover bottom portion and through which slot the shaft 15 of the wormwheel normally extends.

Pivoted upon this sloping cover bottom portion 31^B is a control lever which has the free end of its actuating arm 40 extending outward through an aperture 41 in that cover portion, and which lever has its other arm 42 disposed for engaging the worm-wheel shaft 15 to press that shaft away from a vertical plane diametric of the fan shaft when the control lever is swung to the position shown in Fig. 12, thereby making the oscillating gear and linkage arrangement inoperative. However, when the control lever is moved to its opposite position of Figs. 11 and 13, the arm 42 is spaced from the worm-wheel shaft, thereby allowing the spring 26 to press the worm-wheel against the fan shaft so as to make the oscillating part of my mechanism operative. By pivoting the control lever on a cover part which slopes rearwardly upward, I dispose this lever for convenient digital operation, and by shaping the cover to match the configuration of the motor casing, I can readily make it conform to the general design of my appliance. To prevent the lever from slipping out of its last-named or operative position, I preferably concave the free end to the lever arm 42 so that this arm end will partly straddle the shaft of the worm-wheel.

However, while I have heretofore described my selectively oscillating and non-oscillating electric fan in an embodiment in which the supporting lug 2 is in itself supported by a pedestal, so that this lug constitutes the supporting member for the fan, motor and oscillating mechanism assemblage, and also have described numerous important structural details, I do not wish to be limited in these respects. Obviously, many changes might be made from the above described construction and arrangement without departing either from the spirit of my invention or from the appended claims.

I claim as my invention:

1. In an oscillating electric fan, a supporting member; an electric motor and fan assembly including a fan shaft rotated by the motor, the shaft having a threaded portion; means pivoting the said assembly upon the supporting member on a pivoting axis trans-

verse of and intersecting the fan shaft; and a mechanism interposed between the supporting member and the said assembly for oscillating the assembly about the pivoting axis; the mechanism including a worm-wheel meshing with the threaded shaft portion and supported by the said assembly with the freedom for limited movement toward and away from the said shaft portion, a worm shaft fastened to the worm-wheel, a bracket spaced from the fan shaft and slotted to journal and guide the worm shaft with freedom for movement toward and away from the fan shaft, and spring means normally urging the worm shaft towards the fan shaft and pressing the worm-wheel against the said threaded shaft portion.

2. An oscillating electric fan as per claim 1, in which the mechanism includes spring means for pressing the worm wheel against the said shaft portion; and in which the worm-wheel has an initially cylindrical periphery, and is of a material sufficiently softer than the shaft so that the thread of the shaft will cut the worm tooth formation.

3. In an oscillating electric fan, a supporting structure; an electric motor and fan assembly including a fan shaft rotated by the motor, the shaft having a threaded portion; means pivoting the said assembly upon the supporting member on a pivoting axis transverse of and intersecting the said shaft; and a mechanism interposed between the supporting member and the said assembly for oscillating the assembly about the pivoting axis; the mechanism including a worm-wheel meshing with the threaded fan shaft portion, a worm shaft fast on the wheel, and a bracket fast with respect to the motor and having two bearing portions spaced longitudinally of the worm shaft, in which portions the worm shaft is journaled with freedom for limited movement in a plane diametric of the worm shaft and at right angles to the fan shaft.

4. An oscillating electric fan as per claim 1 in which the mechanism also includes a linkage interposed between the worm shaft and a portion of the supporting member; a cover attached to the motor and housing the worm-wheel and the said threaded shaft portion; the cover having an opening through which the worm shaft extends, the linkage being disposed exteriorly of the cover, and

means mounted on the interior of the cover for moving the worm-shaft away from the fan shaft and latching the worm-shaft in a position in which the worm-wheel is out of engagement with the fan shaft, the last named means having a digitally actuatable portion extending through the cover.

5. In an oscillating electric fan, an assemblage as per claim 1, in which the bracket has spaced arms both parallel to and at the same side as the said shaft portion; the said arms having aligned perforations through which the worm shaft extends, the perforation in the bracket arm nearest the worm wheel being elongated along a plane longitudinal of the worm shaft and at right angles to the fan shaft, and the perforation in the other bracket arm being only slightly larger than the diameter of the worm shaft.

6. An oscillating electric fan as per claim 1, including manually operable means for engaging the worm shaft and moving the worm shaft to a position in which this worm shaft holds the said wheel out of engagement with the fan shaft.

7. An oscillating electric fan as per claim 1, including manually operable means for engaging the worm shaft and moving the worm shaft to a position in which this worm shaft holds the said wheel out of engagement with the fan shaft; and a cover attached to the motor and housing the worm-wheel and the threaded shaft portion, the said manually operable means being supported by the cover; the manually operable means comprising a lever pivoted upon the cover and having the free end of one lever arm adapted to engage the said worm shaft, the other arm of the lever projecting through the cover, the said free arm end being concaved toward the worm shaft so as to interlock with that shaft when the lever is in a position in which it holds the worm-wheel out of engagement with the fan shaft.

8. An oscillating fan as per claim 3, in which the two bearing portions of the bracket are disposed one above the other, and in which the upper of the said portions underhangs the worm wheel so as to support the worm wheel and the worm shaft.

Signed at Chicago, Illinois, December 24th, 1931.

BERNHART A. BENSON.
